Inventor:
Harry L. Lechler

By John C. Hegdon
Attorney.

UNITED STATES PATENT OFFICE.

HARRY L. LECHLER, OF ST. LOUIS, MISSOURI.

POT-HOLDING ATTACHMENT FOR FAUCETS.

1,420,197.

Specification of Letters Patent. Patented June 20, 1922.

Application filed February 2, 1922. Serial No. 533,541.

To all whom it may concern:

Be it known that I, HARRY L. LECHLER, a citizen of the United States, residing at St. Louis, in the State of Missouri, have invented 5 certain new and useful Improvements in Pot-Holding Attachments for Faucets, of which the following is a specification containing a full, clear, and exact description, reference being had to the accompanying 10 drawings, forming a part hereof.

My invention consists in the novel construction and combination of parts herein-after particularly described and distinctly claimed.

15 The object of my invention is to provide an improved hook or hooked-support attachment for water-faucets, particularly for use upon the faucets of kitchen sinks; whereby pots, kettles, and other bailed utensils may 20 be supported while water from such faucets is flowing into them, and thereby obviate the necessity of supporting said utensils by hand during the filling of same with water from said faucets; and which attachment 25 shall be very simple in construction and operation, low in cost, and durable and reliable in use upon said faucets.

In the drawings,

Fig. 1 is a side-elevation of a faucet having my invention applied thereto.

Fig. 2 is a horizontal section through the same, on line 2—2 of Fig. 1.

Fig. 3 is a side-elevation of a modified form of the invention, detached from the 35 faucet, and

Fig. 4 is a top plan view of the modified form of the invention, removed from the faucet.

The numeral 1 designates the hook member, which is to be made of any suitable 40 strong and durable metal or other material, and which is adapted to project centrally of the faucet nozzle 2, directly above the same, so as to support the bailed vessel or 45 utensil centrally below the said nozzle.

Formed integral with the rear portion of 50 said hook-member 1 is a semicircular clamp-member 3, the rear end of which is formed by a perforated ear 4.

A recess or shoulder 5 is formed in a reduced vertical wall 6, which connects said hook-member 1 and said clamp-member 3,

and said wall is provided with a perforation, through which is passed a bolt or screw 7, for clamping a detachable clamping member 8 in position.

Said detachable clamping-member 8 has a perforated ear 9 at its forward end, and said bolt or screw 7 is passed through the perforation of said ear.

The rear end of said detachable clamping-member 8 may be connected to the perforated ear 4 of the said clamp-member 3 by a bolt or screw 10 passed through the perforations of the rear overlapping perforated parts, 65 or (as shown in Figs. 3 and 4) the rear end of said detachable clamping-member may be provided with a reduced extension 11, in place of a perforated ear, which detachably connects the parts by being inserted in 70 the perforation of said perforated ear 4 of said clamp-member 3.

In operation, by tightening-up the bolt or screw 7 at the front of the device, (in either form of my invention), the hook-member 1 will be detachably and firmly held in the position in which it is shown; and bailed vessels or utensils that are hung upon said hook-member will be supported while water or other liquid runs from said faucet-nozzle 2; thereby relieving the operator's hand from the trouble and necessity of supporting the vessels or utensils while being filled.

I claim:

85 A hook-attachment for faucets, comprising a hook-member having a semicircular clamp-member integral therewith, said clamp-member at the junction of said members being of reduced section; a second semicircular clamp-member adapted to engage at one end said reduced section, and at its other end the opposite end of said first-named clamp-member; and means for interconnecting said clamp-members at both ends 90 95 for adjustment of said members on a support.

In testimony whereof, I have signed my name to this specification in presence of two subscribing witnesses.

HARRY L. LECHLER.

Witnesses:

HENRY L. HIGDON,
EDNA E. CONRAD.
